UNITED STATES PATENT OFFICE.

RUDOLPH SIEBERT, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

49,938.

Specification for Design.

Patented Nov. 21, 1916.

Application filed August 30, 1916. Serial No. 117,813. Term of patent 3½ years.

To all whom it may concern:

Be it known that I, RUDOLPH SIEBERT, a citizen of the United States, and a resident of the city of Rochester, county of Monroe, and State of New York, have invented a new, original, and ornamental Design for Buttons, of which the following is a specification.

My design is represented in the accompanying drawing, in which:

Figure 1 is a plan view. Fig. 2 is an elevation showing one of the corners of the button. Fig. 3 is an elevation showing one of the sides of the button.

The button is pyramidal in shape, the upper portion of which is flat and the sides of which are provided with parallel corrugations. The corner edges are smooth, but slightly indented in line with the depressions of the corrugations. The bottom of the button is substantially flat at the outer portions thereof and is provided with a central projection as shown.

I claim:

The ornamental design for a button substantially as shown and described.

In witness whereof I have hereunto set my hand at the city of Rochester, in the county of Monroe and State of New York, this 25th day of August, 1916.

RUDOLPH SIEBERT.

In presence of—

N. D. HULBURT,
EARL A. WELLER.
